(57) **CLAIM**

The ornamental design for a bag for packaging as shown and described.

DESCRIPTION

FIG. 1 is a perspective view of a bag for packaging, showing our new design;

FIG. 2 is a front view thereof;

FIG. 3 is a rear view thereof;

FIG. 4 is a top plan view thereof;

FIG. 5 is a bottom plan view thereof;

FIG. 6 is a right side view; the left side view being a mirror image thereof; and,

FIG. 7 is an enlarged perspective view of the portion of FIG. 1 inside the dash-dot-dot broken line square indicated by the reference number 7; and,

FIG. 8 is an enlarged perspective view of the portion of FIG. 2 inside the dash-dot-dot broken line square indicated by the reference number 8.

The even-length broken lines shown in the drawings represent portions of the bag for packaging that form no part of the claimed design. The dash-dot-dot broken lines depict areas of enlargement in FIGS. 1 and 2 and the boundary of the corresponding enlarged views in FIGS. 7 and 8. The dash-dot broken lines shown in FIGS. 1, 2 and 7 depict the boundary between the claimed portion and the non-claimed portion, and form no part of the claimed design.
